SMOKING PIPE

Albert Partin, Livingston, Mont.

Application May 15, 1946, Serial No. 669,972

1 Claim. (Cl. 131—203)

1 This invention relates to pipes for smoking tobacco, and in particular a pipe having a bowl which is so constructed that moist products of combustion containing nicotine and other products that normally settle in the lower part of the bowl, pass through a small opening in the center of the bottom of the bowl and into a cartridge of absorbent material in a perforated cylindrical container positioned in a pocket below the bowl.

The purpose of this invention is to provide means in a smoking pipe for absorbing objectionable products such as moist products resulting from burning tobacco whereby smoke free from objectionable matter is drawn through the pipe stem into the mouth of the smoker.

The object of this invention is, therefore, to provide means for incorporating a cartridge of absorbent material in the lower part of a pipe so that moist products of combustion resulting from burning tobacco in the pipe pass downwardly by gravity into the cartridge.

Another object of the invention is to provide a pipe having in a pocket under the bowl a cartridge of absorbent material which will absorb the nicotine and effectively prevent it from flowing through the stem and mouthpiece of the pipe to the mouth of the person smoking the pipe.

Another object of the invention is to provide a pipe of this character wherein a cartridge of absorbent material is placed in a cylindrical container which is thrust into place through the open rear end of the pocket under the bowl of the pipe.

Another object of the invention is to so form the container that it may be easily opened for removal of a cartridge and insertion of a new cartridge.

Another object of the invention is to provide a pipe which is clean, cool smoking and very simple in construction.

The invention is illustrated in the accompanying drawing wherein:

Figure 1 is a sectional view taken longitudinally through a pipe of the improved construction;

Figure 2 is a view taken along the line 2—2 of Figure 1;

Figure 3 is a view showing the pipe in section taken on line 3—3 of Figure 2, with the strainer in elevation;

Figure 4 is a view taken along the line 4—4 of Figure 3;

Figure 5 is a perspective view looking at the outer end of the filter or strainer, a portion being shown in section;

Figure 6 is a view similar to Figure 5 looking at the inner end of the filter.

2

Figure 7 is a side view showing the container of the filter opened for removal or insertion of a cartridge.

The improved pipe of this invention is formed with a body having a bowl 1 from which a stem 2 extends and the stem is provided with a socket 3 for receiving the small end portion 4 of a mouthpiece or tip 5. The stem is provided with a reinforcing sleeve 6 and the bore 7 of the stem is positioned in registering relation with the bore 8 of the mouthpiece.

The lower part of the bowl and the adjoining part of the stem are provided with an enlarged portion 10 which is provided with a longitudinally disposed bore providing a pocket 11 the outer end of which is open. The lower part of the bowl is provided with an opening 12 that provides communication between the bowl and pocket. The inner end of the bore or pocket 11 is connected with the bore of the stem through a passage 13 which is inclined upwardly from the pocket 11.

With the parts arranged in this manner the gases of combustion are drawn directly through the stem and mouthpiece and the moist products of combustion pass downwardly by gravity through the opening 12 and into a strainer consisting of a cartridge 15 of absorbent material which is positioned in a perforated cylindrical container 14 in the pocket 11, as described more fully below. Filtered gases may pass from the pocket and cartridge therein through the passage 13 into the stem and mouthpiece.

A strainer is removably mounted in the pocket and consists of a container in which is a cartridge 15 formed of absorbent material. The container is formed of thin metal and of cylindrical shape, the container being split longitudinally to provide a section 16 which is pivotally mounted by a pin 17 on the main section 14 and when closed has edge to edge engagement with the main section of the container so that they cooperate with each other to form a cylindrical container having its open outer or rear end closed by a head or plug 18 carried by the main section 14, the neck 19 of which fits snugly into the front end of the pocket 11. After a cartridge 15 has been fitted into the container the section 16 is moved to the closed position and the head 18 is then grasped and the container inserted into the pocket to the position shown in Figures 1 and 3.

When the pipe is smoked, the moist products of combustion will pass downwardly through the opening and will be absorbed by the cartridge 15. Also any undesirable matter including saliva that may be in the smoke passage 8 may flow down the inclined passage 13 to be absorbed by the

cartridge. When the cartridge has absorbed as much as it will hold the head 18 is grasped and the container withdrawn from the pocket. The section 16 is then swung to the opened position shown in Figure 7, the cartridge removed, and a new cartridge fitted into the container. The section 16 is then returned to the closed position and the strainer thrust back into the pocket.

Having thus described the invention, what is claimed is:

In a smoking pipe, the combination which comprises a pipe body including a bowl with a stem extended at one side and having a removable tip carried by the stem, said stem and tip having a passage therethrough communicating with the adjacent side of the bowl at the inner end of the passage, said body having a downwardly extended depending section with a cylindrical bore therein parallel to the passage of the stem and tip and spaced therefrom, said body having an orifice in the lower end of the bowl communicating with the bore in the said extended depending section, said depending section having an inclined opening at the inner end thereof providing communicating means between the bore of the depending section and the passage of the stem; a perforated cylindrical container formed of two hinged sec-

tions positioned in the bore of the depending section, a filtering element of absorbent material positioned in the container and a plug carried by the outer end of one of the sections of the container and fitted in the outer end of the bore of the said depending section providing a closure for the said bore.

ALBERT PARTIN.
